Application April 26, 1950, Serial No. 158,168

8 Claims. (Cl. 128—305)

1

This invention relates in general to surgical instruments and more especially to a device of the type used for cutting skin grafts.

In particular, the present invention relates to an improvement in the type of skin-graft cutting instrument disclosed in the patents to Reese Nos. 2,479,185 and 2,479,260 of August 16, 1949, and identified as dermatomes. These instruments embody a body member having a convex working surface to which a skin-graft transfer element is adapted to be temporarily but tautly secured; and a graft-cutting blade which is carried by a yoke supported, in turn, by the body member for rotation relative thereto in substantially spaced parallel relationship for excising a skin graft from a donor surface. In the performance of this operation, considerable care and attention must be exercised by the surgeon as the blade approaches the end of the working surface of the body member, lest the blade override the latter and gouge deeply in to the donor surface. Moreover, there is always present the very real danger that in overriding the working surface of the body member, the surgeon may cut his own wrist with the blade. Also, it has been found that a similar danger exists when applying a skin-graft transfer element such as, for example, a sheet of "Dermatape," to the body member preparatory to excising a skin graft; and when removing the excised skin graft and "Dermatape" from the body member, since in both instances it is necessary for the surgeon to reach over or across the blade-carrying yoke of the dermatome.

An object of the present invention is to provide a superior dermatome by which skin-grafting operations may be performed rapidly, skillfully and without danger of injury to the donor surface or to the operating surgeon.

A further object of the invention is to provide a dermatome with superior stop means for stopping the movement of the blade at the end of the working surface of the body member.

A still further object of the invention is to provide a dermatome with coupling means arranged to stop the blade at the end of its cutting swing, and constructed and arranged to permit the blade to be swung freely into a position of safety so that the skin-graft transfer element of the body member may be applied and removed with facility and dispatch, and without danger to the surgeon.

A still further object of the invention is to provide a dermatome with stop means to stop the rotation of the blade relative to the body mem-

2

ber of the dermatome after swinging through an arc in excess of 360°.

A still further object of the invention is to provide a dermatome with coupling means in the bearing structure of the body member for stopping the rotation of the blade in either direction relative to the body member, after swinging through an arc in excess of 360°.

In general the present invention involves providing a dermatome of the type disclosed in the aforementioned Reese patents with coupling means to limit the relative rotation between the cylindrical body member or drum and the blade carrier at a position adjacent the end of the skin-graft operation and to permit the blade carrier to be swung through an arc in excess of 360° in the opposite direction past this limit. This overcomes any danger of the blade overriding the cylindrical surface of the dermatome during the cutting operation and, in so doing, accidentally cutting the wrist of the surgeon. Furthermore, it permits the blade, when in its non-operating position above the drum, to be swung backwards to a position under the cylindrical working surface, where it will be out of the way and can do no harm. An element of the coupling means is mounted for rotation relative to both the body member and the blade carrier to permit the latter to swing through an arc in excess of 360° in either direction. Moreover, it has been found most desirable to locate the coupling means in the hinge or pivotal connection between the drum and blade carrier.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a perspective view of a dermatome embodying the improved stop means of this invention for limiting the angle of rotation of the blade-carrying yoke relative to the body member of the dermatome, the latter being shown supported on a stand, the base of which is partly broken away;

Fig. 2 is a front elevation partly in section of the bearing structure of the body member of the dermatome, showing details of the improved stop means of this invention;

Fig. 3 is an end elevation in section of the bearing structure on line 3—3 of Fig. 2;

Fig. 4 is an enlarged perspective view of a

flanged bushing which constitutes one of the elements of the stop means of this invention;

Fig. 5 is an enlarged perspective view of a stop sleeve of the improved stop means of this invention, having stop lugs at opposite ends thereof respectively;

Fig. 6 is an enlarged perspective view of a second stop sleeve of the improved stop means of this invention, the second stop sleeve having a stop lug projecting from one end thereof;

Fig. 7 is a schematic end elevation of the body member of the dermatome, showing by broken lines the position of the blade-carrying yoke when engaged against the rest of the supporting stand, and by full lines the position of the yoke when resting against the back of the surgeon's wrist preparatory to excising a skin graft;

Fig. 8 is a broken front elevation of the improved stop sleeves together with a portion of the shaft, showing the relative positions of the stop lugs when the yoke is in its full-line position of Fig. 7;

Fig. 9 is an enlarged fragmentary perspective view of the stop sleeves of Fig. 8, but with the shaft omitted;

Fig. 10 is a schematic view similar to Fig. 7, but showing the blade-carrying yoke by full lines at the end of its cutting or skin-graft excising swing, the broken-line position of the yoke corresponding to its full-line position of Fig. 7;

Fig. 11 is a view similar to Fig. 8, but showing the lugs of the stop sleeves in their respective positions when the yoke is in its full-line position of Fig. 10;

Fig. 12 is an enlarged fragmentary perspective view of the stop sleeves of Fig. 11, with the shaft omitted, but viewing the same from a different angle from the showing of Fig. 9;

Fig. 13 is a schematic view similar to Figs. 7 and 10, but showing the yoke by full lines at the terminus of its movement in a clockwise direction as seen in Fig. 13, from its normal position against the rest of the supporting stand;

Fig. 14 is a view similar to Figs. 8 and 11, but showing the lugs of the stop sleeves in their relative positions when the blade-carrying yoke is in its full-line position of Fig. 13; and

Fig. 15 is an enlarged fragmentary perspective view of the stop means of Fig. 14 similar to Figs. 9 and 12, but viewing the same at a different angle.

Referring now to the drawings for greater detail, and in particular to Fig. 1, the reference character 20 indicates in its entirety a dermatome embodying the improved stop means of this invention. The reference character 21 indicates the stand on which the dermatome is mounted, either when it is not in use, or when a skin-graft transfer element is being applied to or removed from the dermatome, in the manner hereinafter described. The aforesaid stand 21 comprises a substantially rectangular base plate 22 having at one side an upstanding post 23 which carries a dermatome-mounting rod 24 arranged to project outwardly laterally therefrom in vertically spaced substantially parallel relationship to the base plate 22. Projecting laterally from the post 23 in vertically spaced relationship above the mounting rod 24 and toward the back of the stand, is a relatively short finger or stud 25, which is adapted to project into an aperture in the corresponding side plate of the dermatome when the latter is mounted on the aforesaid mounting rod, to prevent the

dermatome from rotating thereon. A suitable latch 26 is provided above the stud 25 for releasably engaging the adjacent side plate of the dermatome, to prevent the latter from accidentally sliding laterally off of the counting rod 24 of the stand. In addition to these principal elements of the stand, the upstanding post 23 includes a backstop or rest 27 for supporting the blade-carrier or blade-carrying yoke of the dermatome. Inasmuch as other details of the stand are ancillary to the invention, further description thereof is deemed unnecessary.

The body member of the dermatome is indicated generally at 28 and comprises a pair of spaced parallel side plates 29 and 30 respectively substantially semicircular in shape and joined along their curved edges by a concavo-convex bottom plate 31. In a preferred construction, the sides of the bottom plate 31 are joined integrally with the corresponding edges of the side plates 29 and 30 respectively as, for example, by forming the body member by a casting. It will be appreciated, however, that the side plates and the bottom plate of the body member may be formed as separate elements and joined together by suitable fastening means.

The side plates include upwardly extending ears 32 and 33 respectively having openings 34 and 35 respectively therethrough, whose centers coincide with the center of revolution of the outer convex working surface of the bottom plate 31.

The body member 28 of the dermatome is provided with a bearing structure by means of which the dermatome is supported when in use, and which also serves to support the blade-carrying yoke 36 which, as hereinafter described, is mounted so as to have reciprocatory movement as well as rotational movement relative to the body member. Referring especially to Fig. 2, the bearing structure of the body member includes a substantially cylindrical supporting sleeve 37, the opposite ends of which are reduced in diameter to form shouldered ends adapted to engage in the apertured ears 32 and 33 respectively of the corresponding side plates of the body member, and to be fixedly secured therein against rotation by brazed joints or equivalent fastening means. Formed in the left-hand end of the supporting sleeve 37, as seen in Fig. 2, are internal threads 50 which are adapted to be engaged by the external threads of a flanged bushing 38 which projects into the corresponding end of the supporting sleeve 37 from the outer face of the corresponding ear 32. The flanged bushing 38 at the opposite end of the supporting sleeve 37 constitutes one of a plurality of elements having coordinated stop surfaces for limiting the rotary movement of the blade-carrying yoke 36 relative to the body member and, in this capacity, is provided with an unthreaded sleeve portion 40 (see Fig. 4), the diameter of which is such that the sleeve portion engages with a press fit in the right-hand end of the supporting sleeve 37, as a consequence of which the right-hand flanged bushing 39 is secured against rotation in the corresponding end of the bearing sleeve. If desired, both of the bushings 38 and 39 may be secured in place by suitable retaining pins 37a, as indicated in Fig. 2. By this expedient, the substantially rectangular stop-lug 41 which constitutes an embossment on the end of the sleeve portion 40 of the flanged bushing 38, is fixedly located in the supporting sleeve 37 of the body member in predetermined relationship to the rear edge 42 thereof (Fig. 1) so that, as used in conjunction with the other

stop sleeves hereinafter described of the stop means, the stop lug 41 will serve to stop the blade-carrying yoke 36 during its cutting swing, substantially at the rear edge 42 of the body member.

Referring again to the threaded bushing 38 in the left-hand end of the supporting sleeve 37, as viewed in Fig. 2, the inner end of the bushing 38 is kerfed, as indicated at 43, so that by inserting a suitable tool in the supporting sleeve from the right hand thereof into engagement with the kerfed end of the left-hand bushing 38, the latter may be tightened up. The cylindrical supporting sleeve 37 also serves as a handle for supporting the dermatome when excising a skin graft and, to this end, may be knurled to provide a good gripping surface.

Journalized in the flanged bushings 38 and 39 respectively of the supporting sleeve or handle 37 for both rotary and reciprocatory movement relative to the body member 28, is a shaft 44, the right-hand end of which is provided with an operating handle 45 by means of which the shaft 44 may be simultaneously rotated and reciprocated in the flanged bushings of the sleeve 37. In order to prevent improper assembly of the shaft in the supporting sleeve and the resultant malfunctioning of the stop means, the shaft 44 is constructed so that it may be assembled in the supporting sleeve 37 from its right-hand end only, and to this end, the left-hand end of the shaft 44 is reduced in diameter, as at 46, to provide an annular shoulder 47. Since the internal diameter of the left-hand bushing 38 is substantially equal to the reduced portion 46 of the shaft, and hence less than the diameter of the annular shoulder 47 of the shaft, the latter can be assembled in the supporting sleeve only by introducing its reduced end 46 into the right-hand bushing 39, the internal diameter of which corresponds substantially to the diameter of the unreduced portion of the shaft, the latter thus being free to extend into the supporting sleeve until the annular shoulder 47 of the shaft abuts the inner kerfed end of the flanged bushing 38. Extending longitudinally of the shaft 44 from its annular shoulder 47 toward its right-hand end, is a keyway 48 which serves to lock a stop sleeve of the improved stop means of this invention to the shaft, as and for the purpose hereinafter described.

The shaft 44 mounts the yoke 36 which carries the cutting blade of the dermatome, the yoke comprising a pair of spaced parallel arms 49-49, having at their free ends apertured hubs 50-50 adapted to be mounted on and suitably secured to corresponding ends of the shaft 44, the lateral spacing of the hubs 50-50 being greater than the distance between the outer faces of the flanged bushings 38 and 39 respectively, as shown especially well in Fig. 2, so as to permit longitudinal reciprocal movement of the shaft in the flanged bushings. To facilitate assembly and disassembly of the yoke and shaft, the hub 50 at the left-hand end of the shaft is secured thereto by a screw indicated generally at 51, while the hub at the right-hand end of the shaft is secured thereto preferably by means of a pin 45a carried by the hub portion of the handle 45 and extending into an aperture of the adjacent hub portion 50 of the yoke, for coupling engagement therewith.

The opposite or outer ends of the arms 49-49 of the yoke are joined by an integral crossbar 52 having a flat outer surface against which a graft-cutting blade or knife 53 is adapted to be clamped by means of a clamping bar 54. The

details of the construction and mounting of the clamping bar 54 are omitted, inasmuch as these features of the dermatome are fully disclosed and described in the Reese patents hereinabove identified, it being sufficient to say that the cutting edge of the knife 53 is positioned and held in close proximity to the outer convex working face of the body member 28 by means of the clamping bar 54, the spacing of the knife with respect to the outer working surface of the bottom plate 31 of the body member being varied by introducing suitable shims between the knife blade and the outer surface of the crossbar 52.

The mechanism for retaining a skin-graft transfer element taut against the outer convex working surface of the bottom plate includes a clamp, indicated generally at 55, mounted between the respective side plates 29 and 30 of the body member and in proximity to the front edge thereof; and a spool, indicated generally at 56, rotatably mounted between the side plates 29 and 30 respectively and in proximity to the rear edge 42 of the body member. Details of the clamp 55 and spool 56 are ancillary to the present invention and hence are omitted for brevity, these features being described in detail in the aforementioned Reese patents. It will suffice to say that the clamp 55 is adapted to be used to secure one end of the skin-graft transfer element 57 to the corresponding end of the body member, the opposite end of the skin-graft transfer element being engaged with the rotatable spool 56, rotation of which serves to draw the skin-graft transfer element tautly about the outer convex working surface of the body member.

As stated at the outset, the body member of the dermatome is adapted to be supported on the stand 21 whenever the dermatome is not in use and when affixing the skin-graft transfer element 57 to the working surface of the bottom plate 31. To these ends, the side plates 29 and 30 respectively of the body member are provided with axially aligned apertures 58 and 59 respectively at the lowest points of the respective side plates, that is to say, directly below the apertured ears thereof, the diameter of each aperture corresponding substantially to the diameter of the aforesaid mounting rod 24 of the stand 21, whereby the body member of the dermatome may be mounted thereon by engaging the mounting rod 24 in the apertured side plates of the body member. When mounted in this manner on the rod 24 of the stand, the stud 25 of the post 23 is adapted to project through an aperture 60 formed in the right-hand side plate 30 adjacent the rear edge thereof, so as to hold the body member 28 of the dermatome from rotating about the mounting rod 24, the body member being releasably held from axial movement off of the mounting rod 24 by engagement of the aforesaid latch 26 with the upper edge of the side plate 29.

The stop or coupling means for limiting the rotary movement of the blade-carrying yoke 36 relative to the body member of the dermatome is included in its entirety within the supporting sleeve 37 of the dermatome, and includes, in conjunction with the keyway 48 of the shaft 44, a plurality of coaxing stop sleeves mounted thereon within the cylindrical sleeve 37. Referring particularly to Figs. 2 and 3, the plurality of stop sleeves is seen to comprise an intermediate sleeve or coupling 61 having at opposite ends thereof respectively laterally projecting stop-lugs 62 and

63 which are in substantially axial alignment and of substantially equal dimensions. As assembled on the shaft 44, the double lugged intermediate sleeve 61 is located adjacent the right-hand end of the shaft, with the stop lug 63 abutting the adjacent end of the flanged bushing 39, which constitutes one terminal stop sleeve. As pointed out above, the inner end of the bushing 39 is provided with an inwardly projecting stop lug 41, which forms an abutment for the stop lug 63 of sleeve 61 and which corresponds in size thereto. The other terminal stop sleeve, mounted on the shaft 44 to the left of the double lugged intermediate sleeve 61, is a single lugged sleeve 64, the right-hand end of which is provided with a laterally projecting stop lug 65, the size of which corresponds to the size of the stop lugs 62 and 63 of the double lugged intermediate sleeve 61. Formed integrally with or otherwise secured to the inner surface of the terminal stop sleeve 64, is a protuberance or key 66 adapted to engage in the keyway 48 of the shaft 44. In the present embodiment of the invention, the key 66 is located slightly nearer the right-hand end of the single lugged stop sleeve 64 than its left-hand end thereof, which left end is adapted to engage the kerfed end of the bushing 39 on assembly of the plurality of stop sleeves within the supporting sleeve 37.

When assembled in the latter, in a manner indicated in the drawings, the single lugged stop sleeve will be keyed or splined to the rotatable shaft 44, and hence will be positively rotated by rotation of the shaft 44 in either direction within the sleeve 37. Due to the relatively long keyway 48, the shaft 44 will also have capacity for longitudinal sliding movement within the stop sleeve 64, as well as rotary movement therewith. Moreover, as assembled on the shaft 44, the stop lug 65 on the single lugged stop sleeve 64 is adapted to engage against the stop lug 62 of the double lugged intermediate sleeve 61, while the stop lug 63 of the latter is adapted to engage the stop lug 41 of the bushing or terminal stop sleeve 39, which is secured in the supporting sleeve 37.

While the term "coupling means," as used hereinabove with specific reference to the drawings, includes the three sleeve elements 39, 61 and 64, it is to be understood that, as used in the appended claims, this term, considered in its broader aspect, refers to any coupling arrangement between the body member and the blade-carrier member which will limit rotation between said members in either direction through an angular range in excess of 360°. Thus, broadly speaking, the coupling means may be considered to be the means intermediate and rotatable relative to both said members which, in turn, have provision for interengagement with said coupling means. Accordingly, in the specific embodiment of the invention disclosed in the drawings, the coupling means can also be considered to be only the intermediate sleeve 61, while the body member has provision, by means of sleeve 39, for interengagement with sleeve 61 and the blade-carrier likewise has provision, by means of sleeve 64, for similar engagement with the sleeve 61.

In order to limit rotation of the blade carrier or yoke relative to the body member so as to prevent overtravel of the knife blade during a skin-graft excising operation and to make safe the several manual operations required to mount the skin-graft transfer element 51 on the outer convex working surface of the bottom plate 31, 75

the plurality of stop sleeves is assembled on the shaft 44 in a predetermined relationship which is best illustrated in Figs. 7 through 15 inclusive, wherein Figs. 8, 9, 11, 12, 14 and 15 are arranged substantially opposite Figs. 7, 10 and 13, and serve to illustrate the relative positions of the stop sleeves for corresponding positions of the blade-carrying yoke of the dermatome.

To illustrate the operation of the stop means for preventing the blade-carrying yoke from swinging beyond the end 42 of the body member during a skin-graft excising operation, reference may be had to Figs. 7 through 12. In Fig. 7, the blade-carrying yoke 36 is shown by broken lines in its normal position against the rest 27 of the stand. It will be assumed also that the skin-graft transfer element 51 has been stretched tautly over the outer convex working surface of the bottom plate of the body member 28 preparatory to excising the skin graft. With the yoke 36 seated on the rest 27, the stop sleeves within the supporting sleeve 37 of the dermatome are disposed as shown in Figs. 8 and 9, wherein the edge 63a of the lug 63 of the intermediate sleeve 61 is in engagement with the edge 41a of the lug 41 of the flanged bushing 39, while the edge 65a of the lug 65 of the keyed stop sleeve 64 is spaced away from the edge 62a of the lug 62 of the sleeve 61, the edge 62a of the lug 62 being in an angular position which corresponds to the aforesaid edge 63a of the lug 63, as shown in Fig. 9. At this point, it may be mentioned that inasmuch as both the yoke 36 and the keyed sleeve 64 are coupled to the shaft 44 for rotation therewith, angular rotation of the yoke is indicative of identical angular rotation of the sleeve 64. Moreover, for clarity of description and identification, the key 66 used to couple the sleeve 64 to the shaft is shown in Fig. 2 substantially diametrically opposite the arms 49-49 of the yoke.

In carrying out a skin-graft excising operation, the surgeon grasps the supporting sleeve 37, which serves as a handle, in his left hand and swings the blade-carrying yoke 36 clockwise, as seen in Fig. 7, to a position against the back of his left-hand wrist, as indicated by the full lines in the said figure. He then releases the latch 26 and slides the dermatome off of its supporting rod 24, whereupon he proceeds to excise the skin-graft by grasping the yoke handle 45 in his right hand and reciprocating the blade-carrying yoke while simultaneously rotating the yoke in a counterclockwise direction, as seen in Fig. 7, relative to the outer convex bottom plate of the dermatome until the cutting blade on the yoke reaches a point substantially adjacent the rear edge 42 of the body member 28, as seen in Fig. 10, at which point further rotation of the yoke is positively stopped by the relative positions of the stop sleeves. Thus, as the yoke moves through its graft-excising swing, the stop sleeve 64 will be rotated in a counterclockwise direction, as seen in Fig. 9, until the edge 65a of its lug 65 engages the edge 62a of the lug 62 of the sleeve 61, whereupon the latter is picked up and rotated in a counterclockwise direction until the edge 63b of its lug 63 is brought into engagement with the edge 41b of the lug 41 of the flanged bushing 39, whereupon the several parts of the sleeve are held positively against further rotation in the positions shown in Fig. 12, which correspond to the positions of the yoke at the end of the graft-excising swing.

Since rotation of the blade-carrying yoke and

knife is positively stopped adjacent the rear edge 42 of the body member, any possibility of gouging deeply into the donor surface due to inadvertently swinging the blade beyond the rear edge 42 of the body member is precluded. Likewise, the surgeon is protected from inadvertently cutting the wrist of his left hand, by which he is holding the dermatome.

After excising the skin graft, the surgeon swings the blade-carrying yoke 36 back in a clockwise direction from its full-line position, as shown in Fig. 10, to a position on the back of the wrist of his left hand, which position is indicated by the broken lines of the same figure. Thereupon, he mounts the dermatome on the stand by sliding the body member 28 onto the mounting rod 24 in the manner hereinabove described. The stop sleeves within the supporting sleeve 37 will have been simultaneously rotated in a clockwise direction from the positions they have in Fig. 12 to their original positions, as shown in Fig. 9.

In anticipation of removing the skin-graft bearing-transfer element 57 from the body member of the dermatome, the surgeon swings the blade-carrying yoke back against the rest 27 of the stand and releases his left-hand hold on the bearing sleeve 37 of the body member. Since the blade in the yoke 36 is facing away from the rear edge 42 of the body member, the surgeon may unloosen the spool 56 and release this end of the transfer element 57 from the body member without danger to his hands. On the other hand, were he to try to disengage the opposite end of the transfer element from the front edge of the body member with the yoke seated on the rest 27, the proximity of the blade and the direction in which its exposed edge is facing would endanger the surgeon's hands and wrists. Consequently, before unfastening the forward edge of the transfer element 57, the surgeon swings the blade-carrying yoke 36 from its rest 27, as indicated by the broken lines in Fig. 13, in a clockwise direction, so as to bring the blade-carrying yoke and blade to a position beneath the body member of the dermatome, in which position the surgeon's hands and wrists are protected from accidentally engaging the blade while unfastening the forward end of the transfer element from the corresponding edge of the dermatome. It will be apparent that in order to swing the blade-carrying yoke 36 in a clockwise direction to a position beneath the body member 28, the yoke 36 must be able to swing through an angle of more than 360° measured from the end of its skin-graft excising stroke, which position is shown in Fig. 10. The relative positions of the stop sleeves for achieving this result are illustrated in Figs. 12, 14 and 15. In Fig. 12, the sleeves 64 and 61 are shown locked against further rotation in a counterclockwise direction in the manner hereinabove described, which positions of the sleeves correspond to the position of the yoke at the end of the skin-graft excising cutting stroke. As the yoke is rotated back in a clockwise direction, the edge 65a is moved away from the edge 62a of the lug 62 of the sleeve 61 until the edge 65b of the lug 65 engages the edge 62b of the lug 62 of the sleeve 61, which occurs after the sleeve 64 has been rotated through substantially 240°. Thereupon, the edge 65b of the lug 65 picks up the lug 62 of the sleeve 61 and rotates the latter through an angle of substantially 240°, whereupon the edge 63a of its lug 63 engages against the edge 41a of the lug 41 of the

5

flanged bushing, as shown in Fig. 15, to effectively prevent further rotation of the blade-carrying yoke in a clockwise direction, the limit of rotational movement of the yoke being indicated by full lines in Fig. 13.

10

Having unfastened the front edge of the transfer element 57, the latter may be removed from the body member of the dermatome and used in the well known manner, to cover the injured surface.

15

Although the schematic illustration of Figs. 7 through 15 serves to illustrate the principal need for providing a yoke member with stop means adapted to permit the yoke member and blade to swing through an angle of more than 360° in either direction before being stopped, it will be appreciated that the stop means has other and equally important applications, particularly when applying a transfer element 57 to the body member, preparatory to excising a second skin graft. In this instance, a blade will be mounted in the yoke and hence will present a hazard to the surgeon when attaching a new skin-graft transfer element to the body member of the dermatome. Thus, to attach the forward end of the skin-graft transfer element to the front edge of the body member, the surgeon would normally be compelled to reach across the exposed blade of the yoke. However, by providing the improved stop means of this invention, the yoke may be swung around in a clockwise direction to a position of safety beneath the underside of the body member, in which position the surgeon may apply the skin-graft transfer element to the forward edge of the body member with safety. When applying the opposite end of the skin-graft transfer element to the rear edge 42 of the dermatome, the yoke may be swung up to its normal position against the rest 27 of the stand, in which position the blade is directed away and is remote from the rear edge of the dermatome. A further illustration of the safety factor of the stop means is seen in the final step of preparing the dermatome for excising a skin graft, wherein the printed plastic facing of the skin-graft transfer element is peeled off. To perform this step, the plastic facing of the skin-graft transfer element must be cut through at both the front and back edges thereof, and to perform this cutting operation with safety at the front edge of the dermatome, the yoke member may be swung clockwise to a position beneath the body member.

40

45

50

55

60

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a dermatome having a body member with a cylindrical working surface adapted to roll in contact with the skin of a donor and a blade-carrier member mounted to rotate relative to said body member about the axis of said working surface, the combination with said members of coupling means between said body member and said blade-carrier member for limiting the relative rotational movement thereof, said coupling means being supported by at least one of said members, said members having provision for interengagement with said coupling means to limit said relative rotational movement between said

75

members in either direction within an angular range in excess of 360°.

2. In a dermatome having a body member with a cylindrical working surface adapted to roll in contact with the skin of a donor and a blade-carrier member mounted to rotate relative to said body member about the axis of said working surface, the combination with said members of coupling means between said body member and said blade-carrier member for limiting the relative rotational movement thereof, said coupling means being supported by at least one of said members and comprising an element mounted for rotation relative to both said members about said axis, said members having provision for interengagement with said coupling means to limit said relative rotational movement in one direction adjacent the end of said working surface and to permit relative rotation between said members in the opposite direction through an angle in excess of 360° measured from said end of said working surface.

3. In a dermatome having a body member with a cylindrical working surface adapted to roll in contact with the skin of a donor and a blade-carrier member mounted to rotate relative to said body member about the axis of said surface, the combination with said members of coupling means between said body member and said blade-carrier member for limiting the relative rotation between said members which comprises a plurality of more than two coaxing elements arranged in series, the terminal elements of said series being rotatable with said members, respectively, and all the elements of said series being supported by at least one of said members for rotation relative to each other about said axis, said coaxing elements having interengaging stop-surfaces coordinated to limit relative rotation between said members in one direction adjacent the end of said working surface and to permit rotation between said members in the opposite direction through an angular range in excess of 360° measured from said end of said working surface.

4. In a dermatome having a body member with a cylindrical working surface adapted to roll in contact with the skin of a donor and a blade-carrier member mounted to rotate relative to said body member about the axis of said surface and also to move axially relative to said working surface to facilitate cutting, the combination with said members of coupling means for limiting the relative rotation between said members which comprises a plurality of more than two coaxing elements arranged in series, the terminal elements of said series being rotatable with said members, respectively, and all the elements of said series being supported by at least one of said members for rotation relative to each other about said axis, the terminal element rotatable with said blade-carrier member having provision permitting axial movement of said blade-carrier relative thereto, said coaxing elements having interengaging stop surfaces coordinated to limit relative rotation between said members in one direction adjacent the end of said working surface and to permit rotation between said members in the opposite direction through an angular range in excess of 360° measured from said end of said working surface.

5. In a dermatome having a body member with a cylindrical working surface and a blade-carrier member mounted to rotate relative to said body member about the axis of said working surface,

the combination with said members of a plurality of more than two elongated elements carried end-to-end by at least one of said members for rotation relative to each other about said axis, the endmost elements turning in unison with said members, respectively, and the adjacent ends of successive elements having cooperating stop surfaces, respectively, so coordinated that the stop surfaces of all elements limit the relative rotational movement between said body member and said blade-carrier in one direction adjacent the end of said working surface and permit relative rotation between said members in the opposite direction through an angle in excess of 360° measured from said end of said working surface.

6. In a dermatome having a body member with a cylindrical working surface, supporting means on said body member for holding said dermatome when excising a skin graft, a shaft journaled in said supporting means for rotary movement therein relative to said body member and a blade carrier secured to said shaft for rotation therewith about the axis of said working surface; the combination of a plurality of coaxing stop sleeves arranged in longitudinal alignment with each other on said shaft, a first stop sleeve being rotatable in unison with said body member, a second stop sleeve being rotatable in unison with said blade carrier and a third stop sleeve being intermediate said first and second sleeves and rotatable relative to both said sleeves, said coaxing stop sleeves having cooperating stop lugs located on their adjacent ends, respectively, and arranged to be rotated to and from mutual engagement by relative rotation between said shaft and said body member to limit relative rotation between said body member and said blade carrier adjacent the end of said working surface during a skin-graft operation and to permit relative rotation therebetween in the opposite direction through an angle in excess of 360° measured from said end of said working surface.

7. In a dermatome having a body member with a cylindrical working surface adapted to roll in contact with the skin of a donor, supporting means on said body member for holding said dermatome when excising a skin graft, a shaft journaled in said supporting means for rotary and axial movement therein relative to said body member and a blade carrier secured to said shaft for rotation therewith about the axis of said working surface; the combination of a plurality of coaxing stop sleeves arranged in longitudinal alignment with each other on said shaft, a first stop sleeve being rotatable in unison with said body member, a second stop sleeve being splined to said shaft for rotation therewith and permitting axial movement of said shaft relative thereto, and a third stop sleeve being intermediate said first and second sleeves and rotatable relative to both said sleeves, said coaxing stop sleeves having cooperating stop lugs located on their adjacent ends, respectively, and arranged to be rotated to and from mutual engagement by relative rotation between said shaft and said body member to limit the relative rotation between said body member and said blade carrier adjacent the end of said working surface during a skin-graft operation and to permit relative rotation therebetween in the opposite direction through an angle in excess of 360° measured from said end of said working surface.

8. In a dermatome, including a body member having a working surface, means for supporting

13

said dermatome when excising a skin graft, said supporting-means comprising a bearing-structure carried by said body-member; a shaft journaled in said bearing-structure for rotary and reciprocatory movement therein relative to said body-member; a blade-carrier secured to said shaft, said blade-carrier being spaced from said body-member and arranged to be rotated relative thereto by rotation of said shaft; the combination of stop-means for said blade-carrying means, said stop-means being characterized by elements carried by said bearing-structure and by said shaft respectively, said elements being arranged to be rotated to and from mutual engagement so as to permit rotation of said blade-carrier through an angle in excess of 360° by rotation of said shaft relative to said bearing-structure both to automatically stop the rota-

tion of said shaft and said blade-carrier at the end of the working surface of said body-member after having rotated in one direction through an angle sufficient to perform a skin-graft excising operation, and to permit said shaft and blade-carrier to rotate freely in the opposite direction through an angle in excess of substantially 360° measured from the said end of the working surface of said body-member.

THOMAS R. ARDEN.
